FIG. 3

FIG. 2

FIG. 1

FIGURE 1 is a front perspective view of a calendar or the like showing my new design as it appears with the expandible element in folded or closed position;

FIGURE 2 is another front perspective view thereof as it appears with the expandible element in open position, the spiral binder being shown partially broken away for convenience of illustration; and

FIGURE 3 is an enlarged side view thereof with parts being shown broken away for convenience of illustration.

The essential features of the design reside in the portions shown in solid lines; conventional numerals and printed matter being shown in broken lines.

The back of the calendar is plain and unornamented.

I claim:

The ornamental design for a calendar or the like, as shown and described.
